FLEXING MACHINE

Herbert J. Willmott, Beverly, Mass., assignor to
United Shoe Machinery Corporation, Borough
of Flemington, N. J., a corporation of New
Jersey

Application September 26, 1938, Serial No. 231,687

13 Claims. (Cl. 12—41.2)

This invention relates to machines for flexing blanks such as soles, and is herein illustrated as embodied in a power-operated machine of the type in which a pair of flexible endless bands are employed to advance the blanks and subject them to flexing treatment while in transit.

Although flexing machines of the endless band type are recognized as superior in some respects to other types when they are in first-class condition, and are preferred by many users because of the facility and speed with which they advance and flex the work-pieces, much trouble has been experienced in former machines of this type in that the bands wear out rapidly and require too frequent replacement with new bands.

I have ascertained that the chief cause of such wearing is due to relative creeping of the work-pieces and the bands, and the consequent friction and rubbing, particularly at points where the bands and the work-pieces pass around segments of the flexing rolls. I have also ascertained that if the bands are unequally tensioned, relative creeping and rubbing are unavoidable, and one or both will be subjected to chafing by the work-pieces.

To overcome the objectionable conditions mentioned above, one improved feature provided by the present invention consists in means arranged to equalize the tension of both bands of a pair not only when the bands are initially set up and adjusted prior to starting them in operation, but also while they are in operation and subjected to periodical and unequal displacement as successive work-pieces pass around the flexing rolls.

The invention also provides improved mechanism for collecting the flexed soles discharged from the flexing mechanism, and for arranging them in feathered relation and conveying them in that relation to a point where they may conveniently be picked up in stacked relation for removal.

In addition, the organization herein illustrated includes automatic mechanism for feeding soles one by one from the bottom of a stack to the flexing mechanism. The feeding mechanism, the flexing mechanism and the collecting and conveying mechanism are so organized and coordinated with respect to their relative speeds of operation that the soles are segregated from each other by the relatively high speed of the flexing mechanism and thereafter aggregated as they are collected on the conveyor, the slow speed of the latter being effective to establish their feathered relation. In this relation they may be readily counted to facilitate picking them up in case-

lots or any other desired number without interrupting the operation of any of the mechanisms or disturbing the order in which they are fed to the flexing mechanism.

Referring to the drawings,

Fig. 1 is a perspective view of an organization embodying the various features of the present invention;

Fig. 2 is a perspective view of the same organization from a different angle;

Fig. 3 is a vertical section not all in one plane but according to line III—III of Fig. 4;

Fig. 4 is essentially a top plan view projected from Fig. 3 except that a portion thereof is in horizontal section as indicated by line IV—IV of Fig. 3;

Fig. 5 is a vertical section through the structure intersected by line V—V of Fig. 3, this structure being at the supply end of the organization;

Fig. 6 is a vertical section of the structure intersected by line VI—VI of Fig. 5, the direction of the view being the opposite of Fig. 3;

Fig. 7 is a sectional elevation of the receiving end of the flexing mechanism as indicated by line VII—VIII of Fig. 3;

Fig. 8 is a sectional elevation of the delivery end of the flexing mechanism as indicated by line VIII—VIII of Fig. 3;

Fig. 9 is a sectional elevation of the structure intersected by line IX—IX of Fig. 3;

Fig. 10 is an elevation of the delivery end of the flexing mechanism viewed in the same direction as Fig. 3 but turned slightly to facilitate projecting Fig. 11 therefrom;

Fig. 11 is an end elevation of the delivery end of the flexing mechanism, the direction of view being toward the receiving end thereof;

Fig. 12 is a vertical section of the structure intersected by line XII—XII of Fig. 4, the direction of view being the same as that of Fig. 11, and

Fig. 13 is a sectional plan view of the structure intersected by line XIII—XIII of Fig. 10 but turned 90° as though projected from Fig. 11.

Referring to Fig. 3, the flexing mechanism comprises a pair of flexible endless carrier bands 15 and 16 cooperatively related to engage the opposite sides of an article to be flexed, such as a leather sole 17. These bands are arranged to run on two groups of rolls, each group comprising an anchoring roll 18 at the delivery end of the flexing range, a tensioning roll 19 at the receiving end of that range, and one or more intermediate flexing rolls 20 of which two are provided in each group in the illustrative construction. These rolls are arranged to flex each sole twice in one

5

55

direction and twice in the opposite direction. The axes of the rolls 18 and 20 are fixed but those of the rolls 19 are movable to maintain equal tension of the bands notwithstanding displacement of the bands alternately as the soles pass around the flexing rolls 20.

Referring to Fig. 8, the two anchoring rolls 18 are fixed respectively to shafts 21 and these shafts are provided with intermeshing spur gears 22 by which they are caused to rotate in opposite directions at equal speeds. Rotation derived from an electric motor 25 (Fig. 2) is transmitted to the lower shaft 21 by a belt 24 and a driven pulley 23. Again referring to Fig. 8, the lower shaft 21 is also provided with a pulley 26 for driving a transmission belt 27 and with a pulley 28 for driving a transmission belt 29. The belt 27 drives a feeding mechanism at the supply end of the organization and the belt 29 drives a conveyor at the delivery end of the organization.

The lower shaft 21 is journaled in three roller-bearings 30, the middle bearing being mounted in the main frame 31 of the flexing mechanism, one of the outer bearings being mounted in a bracket 32, and the third bearing being mounted in a removable plate 33 detachably secured to the frame 31 to provide for inserting the bands 15 and 16 through an opening 34 (Fig. 8) in the frame. The removable plate 33 is secured to the frame 31 by nuts 35 screwed on the ends of tie-rods 36 of which four are provided. The plate 33 also carries a roller-bearing 30 for the upper shaft 21 and a similar roller-bearing 30 for each of the four flexing rolls 20, the complementary bearing for these rolls being mounted in the opposite wall of the frame 31.

The tensioning rolls 19 are mounted in improved means (Fig. 7) by which the tension of the bands 15 and 16 is equalized under all conditions. For this purpose, the shafts 40 of these rolls are journaled in a tension-equalizer comprising two similar rockers 41 and two tie-rods 42 by which the rockers are rigidly connected in spaced-apart relation. The rockers 41 are mounted on coaxial trunnions 43, the axis of which is midway between the axes to the rolls 19 and parallel thereto. The trunnions 43 are movable laterally toward and from the anchoring rolls 18, and for this purpose they are affixed to a tensioning structure consisting of an essentially rectangular open frame comprising side members 44 and tie-rods 45. This frame is suspended from the upper portion of the frame 31 to which it is connected by a horizontal pivoting rod 46. The lower tie-rod 45 (Fig. 3) is connected by a pivot pin 47 with one end of a screw-rod 48 surrounded by a compression spring 49. The opposite end of the rod 48 has a smooth bearing in a crossbar 50 which, as shown in Fig. 8, is arranged on trunnions 51. The rod 48 may slide endwise in the bar 50 and is normally stressed in the direction to tension the bands 15 and 16 by the compression spring 49, one end of which is seated against the bar 50 and the opposite end against a nut 52 on the rod. By turning this nut to compress the spring, the initial tension of the bands 15 and 16 may be regulated. Since the above-described tension equalizer is free to rock on the trunnions 43 (Fig. 7), each band reacts against the other with equal tensioning force as first one band and then the other is displaced by a sole being carried around successive flexing rolls 20.

Since the bands 15 and 16 derive their moving force exclusively from the anchoring rolls 18 at

the delivery end of the flexing range, the operative runs of the bands are pulled rather than pushed through the flexing range and are thus maintained as firmly as possible in contact with the interposed soles and the flexing rolls. Consequently, adequate traction is assured and relative creeping of the bands and the soles is eliminated.

As pictured in Fig. 3, the supply end of the organization is at the left of the flexing bands 15 and 16. The main frame of the machine may be provided with a supply table 55 on which the operator may stack the unflexed soles in case lots or in any desired numbers. From this table he may transfer a stack of soles to an automatic feeding mechanism by which they are fed endwise, one by one, from the bottom of the stack to the flexing bands 15 and 16 at a point between the tensioning rolls 19. The feeding mechanism forms the bottom of a stall or magazine comprising two vertical confronting cheeks or walls 56, a transverse wall or gate 57 and a flexible endless carrier band 58 that supports the stack of soles. This carrier band 58 is arranged to run on rolls 59, 60 and 61 of which the roll 59 is driven. Roll 25 61 is adjustable to maintain the desired tension of the band and roll 60 serves merely to prevent the band from sagging between the two other rolls. The rolls 60 and 61 are journaled in an adjustable bolster 62 affixed to two parallel supporting rods 63. These rods are arranged to slide in bearings in a bracket member 64 of the main frame and they serve also to support the supply table 55. The tension of the carrier band 58 may be regulated by turning a screw 65, the thread of which engages the bolster 62 and one end of which abuts a portion of the bracket 64.

The shaft of the roll 59 (Fig. 5) is journaled in bearings secured to the bracket 64 and projects beyond one of the bearings to support a pulley 66 and to be driven by the belt 27 described in connection with Fig. 8. The diameter of the driving pulley 26 and the driven pulley 66 are such as to drive the carrier band 58 at a speed less than that of the flexing bands 15 and 16. Consequently, although the band 58 alone would feed the soles from the bottom of the stack in the magazine with little or no appreciable gaps between them, the soles become segregated from each other as the flexing bands 15 and 16 accelerate their speed of travel, the gaps thus developed being preferably about one inch to insure enough clearance for stacking the discharged soles in feathered relation on a slow-speed conveyor 80 (hereinafter described) by which they are carried sidewise, that is, at right angles to their general path of travel in the flexing mechanism.

The transverse wall or gate 57 (Figs. 3, 5 and 6) may be adjusted up and down by a screw 67 to regulate the depth of the gap between its lower edge and the carrier band 58 in accordance with the thickness of the soles to be flexed. In practice, this gap will be slightly greater than the thickness of one sole but less than the aggregate thickness of two soles. For the purposes of this regulation and control the vertical side edges of the wall 57 are arranged to slide in grooves in a stationary block 68 and the upper portion of the wall is provided with a flange arranged to occupy a groove in the screw 67 to receive adjusting movement from the screw.

The confronting side walls 56 of the sole-magazine are capable of being adjusted toward and from each other in accordance with the width of 75

the soles. For this purpose two pairs of parallel horizontal guide rods 69 are arranged to slide in bearings in the block 68 and each pair carries one of the walls 56. An improved feature of the invention is embodied in the means now about to be described for connecting and adjusting the walls 56 to insure symmetrical but opposite movements thereof and to facilitate assembling the parts in the desired relation.

The adjusting element for this purpose is a compound screw comprising a portion having a coarse thread 70, a portion having a fine thread 71, a smooth cylindrical portion 72, a knob 73, and a collar 74. For convenience of description, the side walls 56 will be treated without regard to the fact that each of them comprises a thin sheet metal plate and a reinforcing member to which the guide rods 69 are affixed. As shown in Fig. 5 the smooth stem portion 72 of the compound screw extends through one of the walls 56 and is free to turn therein, the knob 73 and the collar 74 serving merely to communicate axial movement of the screw to this wall without appreciable lost motion. The fine thread 71 engages a corresponding thread in the block 68 to produce this motion. The coarse thread 70 is pitched in the same direction as the fine thread 71 but the ratio of the pitches is as two to one. The coarse thread engages a corresponding coarse thread in a tube 75 partially nested in a socket in the block 68 and anchored to the other side wall 56 by a set-screw 76. Before attaching the knob 73 to the screw, in the process of assembling the parts, the fine thread 71 may be inserted through the block 68 from left to right, after which the collar 74 and one of the walls 56 may be slipped on the portion 72, and finally the knob 73 may be pinned or otherwise affixed to the outer end of the portion 72. The tube 75 may thereafter be screwed along the coarse thread 70 from left to right and the left hand wall 56 may be slid from left to right until its distance from the block 68 is equal to that between the right-hand wall and the block. Then, if necessary, the tube 75 may be screwed in or out to place its left-hand end in flush relation to the corresponding wall 56, and its connection with that wall fixed by tightening the set-screw 76. When the parts are thus assembled, the walls 56 will be equally distant from the median vertical plane of the carrier band 58 and rotation of the compound screw will adjust them toward or from each other with equal increments of movement.

Although the soles 17 become segregated from each other by the high speed of the flexing bands 15 and 16, they finally become aggregated in feathered relation on the endless flexible conveyor 80 the speed of which is considerably less than that of the band 58. When viewed as in Fig. 4, the feathered soles deposited on the conveyor 80 are carried sidewise in a direction from top to bottom of this figure. Their direction of travel in the final stage is also indicated by an arrow in Fig. 1.

Referring to Figs. 3, 10 and 11, the path of exit of the soles from the flexing bands 15 and 16 is normally obstructed by a retarding device consisting of a tongue 81 of flexible sheet material such as leather or rubber. This tongue is secured by its upper margin to a convenient portion of the frame 31, its lower margin intersecting the normal path of the soles and being free to be deflected as represented in Fig. 3. The retarding device is desirable in practice because the soles

travel through the flexing mechanism at the rate of about 260 per minute.

Once the soles are free and clear of the flexing bands, their leading ends strike an abutment 82 by which they are arrested in register with the conveyor 80 and an inch or two above it. The soles may bounce back slightly from the abutment 82, but since their speed of travel at the time of impact is considerably retarded by the tongue 81, their recoil from the abutment 82 is only a small fraction of an inch. Nevertheless, it is desirable to align their leading ends as they become stacked on the conveyor 80, to the end that they may be the more readily handled thereafter. Accordingly, as shown in Fig. 4, the effective surface of the abutment 82 is skewed or back-pitched with respect to the path of travel of the conveyor, and as the soles are carried along by the conveyor the abutment operates with a camming effect to align them. The abutment is adjustable toward and from the flexing mechanism, and for this purpose it is affixed to an adjustable angle-iron 79 mounted on a supporting bar 78 and secured thereto by a wing-nut 77 and a screw, the connection including a slot in the angle-iron.

As shown in Figs. 4 and 11, the conveyor 80 runs on a driven roll 83 and a tensioning roll 84. The upper run of the conveyor is supported also by a flat horizontal wall 54 of a hollow frame in 30 which the rolls 83 and 84 are mounted. The shaft of the tensioning roll is journaled in blocks 85 adjustable toward and from the driven roll and maintained at the desired distance from the latter by adjusting screws 86 of which one appears in Fig. 12. The driven roll 83 receives slow-speed rotation from a reducing gearing comprising a worm-wheel 87, a worm 88, a shaft 89, a pulley 90 and the belt 29 hereinbefore described in connection with Fig. 8.

The speed of the conveyor 80 in comparison with the rate at which the soles are discharged from the flexing mechanism is such as to establish a feathered relation of the soles with one side edge of each sole in contact with the supporting surface of the conveyor. This feathered relation and the engagement of each sole with the conveyor are illustrated in Fig. 11. Consequently, the tractive effect of the conveyor is applied to the feathered soles both individually and collectively and the feathered relation is maintained after the soles pass beyond the delivery end of the conveyor and slide along stationary work-supporting means designed to facilitate picking up the soles in case lots or other number without disturbing the order in which they are stacked.

The stationary work-supporting means comprises a frame including side members 91, cross-bars 92 connecting them, and a sloping grid or track made of a series of parallel rods 93 on which the feathered soles may slide with little resistance. The ends of the shaft 94 of the tensioning roll 84 are extended beyond the bearing blocks 85 to provide trunnions for supporting the adjacent ends of the side members 91, the receiving ends of the rods 93 being thereby supported virtually in tangent relation to the adjacent segment of the conveyor 80. One of the crossbars 92 at the opposite ends of the side pieces 91 extends through the upper section of a telescopic supporting post 95 in which a set-screw 96 is provided to regulate the downward slope of the rods 93 from the conveyor 80. In practice, it is desirable to slope these rods enough to counter-

- act the friction of the soles in contact with them and thus to avoid too much resistance to the advancement of the feathered soles. On the other hand, the degree of slope of the rods should not exceed the angle of repose. At the same time, it is desirable to prevent the soles at the leading end of the stack from falling off the delivery ends of the rods 93, and for this reason the rods are curved upward as indicated at 97 in Fig. 12.
- 10 Consequently, if the attendant permits too great a number of soles to be accumulated on the rods 93 they will not fall off the ends of the rods but will gradually become consolidated into a more compact mass as the accumulation increases.
- 15 The rods 93 are spaced one from another about one inch, more or less, to enable the attendant to insert his fingers between them when picking up a group of soles to be tied in a bundle and taken away.
- 20 Having thus described my invention, what I claim as new and desire to secure by Letters Patent of the United States is:
1. A sole-flexing machine comprising a pair of flexible endless carrier bands cooperatively related to engage the opposite faces of a sole lying between them, two groups of rolls on which said bands respectively are arranged, operating means for rotating a plurality of said rolls to drive said bands, each of said groups including an anchoring roll, a tensioning roll and one or more flexing rolls, and tensioning mechanism common to both of said tensioning rolls and arranged to cause them to react with equal force, each upon the other, to maintain equal tension of the bands under all conditions.
  2. A sole-flexing machine as defined in claim 1, in which said tensioning mechanism includes an adjustable tension-regulating device so arranged that said bands partake equally of its regulating effects.
  3. A sole-flexing machine as defined in claim 1, in which the axes of said anchoring rolls and of said flexing rolls are fixed.
  4. A sole-flexing machine as defined in claim 1, in which said tensioning rolls are located at one end of the sole-engaging range of the bands, and said anchoring rolls at the opposite end of said range.
  5. A sole-flexing machine as defined in claim 1, in which said tensioning rolls are located at the receiving end of the sole-engaging range of the bands, and said anchoring rolls at the discharging end of said range and driven by said operating means to pull the sole-engaging runs of the bands.
  6. A sole-flexing machine comprising a pair of flexible endless carrier bands cooperatively related to engage the opposite faces of a sole lying between them, two groups of rolls on which said bands are arranged, means for rotating a plurality of said rolls to drive said bands, each of said groups including an anchoring roll, a tensioning roll and one or more intermediate flexing rolls, a tension equalizer in which said tensioning rolls are journaled, a movable supporting structure in which said tension equalizer is mounted, and resilient means arranged to stress said movable structure to tension said bands through the agency of said equalizer.
  7. A sole-flexing machine as defined in claim 6, in which said tension equalizer is arranged to rock on an axis at one end of the sole-engaging range of said bands, and said movable structure is arranged to rock on another axis parallel thereto.

8. A machine for operating on soles comprising power-driven mechanism arranged to transfer soles individually and lengthwise from a receiving locality to a discharging locality and thereby subject them to an operation while in transit, means arranged to support a plurality of soles in stacked relation adjacent to said receiving locality, power-driven mechanism for feeding the soles lengthwise one at a time from the bottom of the stack to said transferring mechanism, an endless conveyor arranged to carry the discharged soles widthwise from said discharging locality, a power-driven means for operating said conveyor at a speed such as to establish a feathered relation of the soles discharged thereon by said transferring mechanism with one edge of each sole in contact with the supporting surface of the conveyor, and an abutment arranged to arrest the soles projected over the conveyor by said transferring mechanism, the sole-engaging surface of said abutment being back-pitched at a slight angle with respect to the path of the conveyor to align the leading ends of the soles with a slight movement of translation lengthwise of the soles in consequence of their widthwise movement.
9. In a machine having power-driven mechanism for transferring thin flat blanks edgewise and individually from a receiving locality to a discharging locality and thereby subjecting them to an operation while in transit, the combination comprising power-driven means arranged to feed blanks successively to said transferring mechanism, an endless conveyor arranged to carry the blanks from said discharging locality, power-driven means for operating said conveyor at a speed such as to establish feathered relation of the blanks discharged thereon by said transferring mechanism, and stationary work-supporting means arranged to form an extension of the work-supporting run of said conveyor, said stationary means including a declined portion the slope of which is within the angle of repose to maintain the feathered relation of the blanks, and including beyond that portion an upwardly curved portion to consolidate the accumulated blanks into a more compact mass.
10. In an apparatus for handling a series of blanks of sheet material, an endless conveyor and supporting rolls one of which is located at the delivery end of a work-supporting run of the conveyor to form a return bend in the latter, power-driven mechanism arranged to perform an operation on successive blanks and deposit them successively on said conveyor, means driven in timed relation to said mechanism for operating said conveyor at a speed that will arrange the deposited blanks in feathered relation with one edge of each blank in contact with the conveyor, stationary work-supporting means arranged to form a track in line with said run of the conveyor to receive the feathered blanks from the latter, pivotal means by which the receiving end of said stationary means is supported with provision for angular adjustment about the axis of the aforesaid conveyor roll, and adjustable means by which the opposite end of said stationary means may be supported to regulate the grade of the track to a slope within the angle of repose and within the power of the feathered blanks on said conveyor to advance a large number of preceding blanks along said track.
11. A device for centralizing work-pieces with respect to means for operating on them, comprising two confronting cheeks adjustable toward and

from each other in accordance with a lateral dimension of an interposed work-piece, means for supporting and guiding said cheeks, a compound screw having a coarse thread and a fine thread of similar direction or lead and of a two-to-one pitch ratio, a fixture having a fine thread engaging that of said screw, means by which axial movement of said screw as produced by said fine threads is communicated in equal degree to one of said cheeks, and connecting means by which the screw action of said coarse thread is communicated simultaneously to the other one of said cheeks.

12. A device as defined in claim 11, in which said connecting means comprises an internally threaded member engaging said coarse thread and slidably engaging said other cheek, and means by which said internally threaded member and said other cheek may be rigidly secured to each other in adjusted relation.

13. In a machine for treating articles of sheet material individually while in transit, a maga-

zine arranged to support a stack of the articles lying one on another, the bottom of said magazine being an endless carrier band for feeding the article at the bottom of the stack edgewise from the stack, stacking mechanism including an endless carrier band arranged to receive and convey the treated articles, intermediate mechanism including an endless carrier band arranged to transfer the articles from the first-mentioned carrier band and deposit them upon said band of the stacking mechanism, means arranged to treat the articles in process of being transferred by said intermediate mechanism, and power-driven means by which said carrier bands are driven at three different relative speeds, viz., that of said intermediate mechanism faster than said feeding band to segregate the articles, and that of said stacking mechanism slower than said feeding band to aggregate the articles in compact feathered relation.
